FIG. 3

FIG. 4

FIG. 6

FIG. 7

FIG. 1 is a front perspective view of a mountable harrow on a slightly reduced scale, showing my new design, the fragmentary portions of the plow shown in broken lines being for illustrative purposes only;

FIG. 2 is a top plan view thereof;

FIG. 3 is a side elevation thereof, looking in the direction of the line 3—3 of FIG. 2;

FIG. 4 is a bottom view thereof;

FIG. 5 is a rear end view thereof in working position;

FIG. 6 is a rear end view thereof in its folded non-working position, and

FIG. 7 is an enlarged front view thereof, with the fragmentary support member shown in folded position.

I claim:

The ornamental design for a mountable harrow, as shown and described.
